UNITED STATES PATENT OFFICE.

HARRY J. SAUERS, OF GREELEY, COLORADO.

WHEEL-HOLDER.

1,319,536.

Specification of Letters Patent.

Patented Oct. 21, 1919.

Application filed June 20, 1919. Serial No. 305,635.

To all whom it may concern:

Be it known that HARRY J. SAUERS, a citizen of the United States of America, residing at Greeley, in the county of Weld 5 and State of Colorado, has invented new and useful Improvements in Wheel-Holders, of which the following is a specification.

The object of the invention is to provide new and efficient means for securing and holding to the track the car wheel when it is necessary to jack up boxes of the latter for rebrassing. To this end the invention comprises an appropriate clamp adapted to be readily attached to the tread of a track 15 rail and thereafter engage with the car wheel for the purpose of firmly securing the latter to the rail tread, whereupon the journal box may be jacked up for the purpose of refilling with new brass.

20 A further object of the invention is to provide a device of the above mentioned character which is simple in construction, durable and effective in operation and inexpensive to manufacture.

25 Other and further objects appear in the following description wherein the invention is set forth in detail.

To the exact construction in which it is shown and described the invention is not 30 to be restricted. The right is reserved to make such changes or alterations as the actual reduction to practice may suggest in so far as such changes or alterations are compatible in spirit with the annexed 35 claims.

The same numerals of reference designate the same parts throughout the several figures of the drawing, wherein:

40 Figure 1 is a perspective view showing the practical application of the invention.

Fig. 2 is a vertical sectional view of the structure shown in Fig. 1 and taken approximately upon the line where the wheel tread engages the rail tread.

45 Fig. 3 is a side elevational view of the holder.

Fig. 4 is a top plan view thereof.

As shown, the invention is employed for holding the wheel 1 down upon the tread 50 of the rail 2 when the journal box is being jacked up for the purpose of relining. The invention comprises a track engaging element in the form of a frame consisting of a body portion 3 and legs 4 disposed 55 at opposite ends of the body portion with respect to which they are turned at right

angles, so that the plane of the face of the body portion is at right angles to the plane of the faces of the two legs. The two legs toward their free ends are formed with gripping jaws 5 designed to grip the tread 60 of the rail 2 and to this end these jaws 5 are parallel to the body portion 3. Coöperating with the jaws 5 which may be considered the passive jaws there is the active 65 jaw 6 which is generally of the shape of an angle bar, one flange of this jaw engaging under the bottom of the tread of the rail 2 and the other flange lying against the under faces of the legs 4. The active jaw 6 70 is attached to the two legs 4 by means of bolts 7 which pass through slots 8 formed in the legs 4, these slots being formed in the direction of the legs, so that the jaw 6 may be moved in the direction of the 75 length of these legs to permit its engagement with or its disengagement from the tread of the rail.

Carried by that flange of the active jaw 6 which is engaged with the legs 4, there 80 is a wheel engaging member which is formed with a U-shaped portion 9 straddling one flange of the jaw 6, this U-shaped portion being secured to the flange by means of appropriate rivets 10. Extending downwardly from the U-shaped portion, there is an ear 11 through which there loosely passes one end of a screw 12, the latter being formed with a head 13 abutting the ear of one face and having passed diametrically 90 through it a cotter 14 which abuts the ear of the opposite face. The screw member 12 is threadingly engaged in the body portion 3 of the main frame of the device and carries on that end remote from the 95 head 13 a cross handle 15 by which it may be readily turned. Obviously the turning of the handle 15 effects longitudinal movement of the screw 12 through the body member 5 which, being precluded from longitudinal movement with reference to the ear 11, will cause the active jaw 6 to be drawn back toward the body member 3 and away from engagement with the rail tread, thus permitting the jaws 5 of the 105 legs 4 to be readily disengaged from the rail 2 and the device thus removed from connection with the rail.

The U-shaped portion 9 is formed, on top of the flange of the active jaw 6, with an 110 standing portion 16 at the extremity of which there is an inturned ear 17 which,

when the active jaw 6 is in engagement with the rail 2, overhangs the inner circumference of the rim of the wheel 1, whereupon the screw 18 which is threaded through the ear 5 may be set down against the wheel by means of its cross handle 19.

As shown in Fig. 1 of the drawings, the device is attached to a track with the legs 4 disposed in front and back of the wheel 10 tread and with their jaws 5 engaging the track tread. The turning of the cross handle to the right will then move the active jaw 6 into engagement with the track tread on the opposite side from that which is engaged by the jaws 5, this action also moving the wheel clamping element of the device into a position where its screw 15 18 may be engaged with the wheel, as clearly shown in the drawings. The wheel, so long as the device is thus attached, 20 is retained on the track, despite the jacking up of the journal box and the latter therefore may be raised for rebrassing without the difficulty of having the wheel rise 25 with it. When the rebrassing or relining is completed the box may be again seated upon the journal and the device removed from attachment with the wheel and with the track.

30 The invention having been described, what is claimed as new and useful is:

1. A device of the kind described comprising a frame formed with a body portion and a pair of spaced legs connected with 35 the body portion, the legs being formed with passive jaws on their free ends, an active jaw carried by the frame and slidably connected with the two legs, a screw operatively connected with the active jaw and thread- 40 ingly engaged with the body portion of the frame to effect the movement of the active

jaw into and out of engagement with a track tread when the passive jaws engage the latter, and a wheel clamping element carried by the active jaw.

45

2. A device of the kind described comprising a frame formed with a body portion and a pair of spaced legs at opposite ends, the legs being formed with slots in the direction of the length thereof and with 50 passive track tread engaging jaws at their free ends, an active track tread engaging jaw, bolts mounted in the said active jaw and slidably engaging the slots in the legs of said frame, a screw threadingly engaged 55 with the body portion of the frame and operatively connected with the active jaw so that as the screw is turned the active jaw may be moved toward or away from the passive jaws, and a wheel clamping element 60 carried by the active jaw.

55

3. A device of the kind described comprising a frame formed with a body portion and a pair of spaced legs each of which is formed with a passive track tread jaw operatively connected with the frame, means for moving the active jaw toward and away from the passive jaws to connect the frame or disconnect the frame from the track tread, a wheel clamping element carried by 70 the active jaw and formed with an ear, which overhangs the inner periphery of a wheel rim when the active and passive jaws are engaged with a track tread in front and in back of a wheel, and a screw passing 75 through said ear for clamping engagement upon the wheel as and for the purpose herein specified.

65

In testimony whereof he affixes his signature.

HARRY J. SAUERS.
